UNITED STATES PATENT OFFICE.

GEORGE S. CROSBY, OF BRIDGEPORT, CONNECTICUT.

TOY LOCOMOTIVE.

SPECIFICATION forming part of Letters Patent No. 330,299, dated November 10, 1885.

Application filed April 23, 1884. Renewed March 14, 1885. Serial No. 158,889. (No model.)

To all whom it may concern:

Be it known that I, GEORGE S. CROSBY, a citizen of the United States, residing at Bridgeport, in the county of Fairfield and State of Connecticut, have invented certain new and useful Improvements in Toy Locomotives; and I do hereby declare the following to be a full, clear, and exact description of the invention, such as will enable others skilled in the art to which it appertains to make and use the same.

My invention relates to certain novel and useful improvements in the construction of toy locomotives, and has for its object to provide a toy of this description, whose running-gear shall closely resemble that of the steam-locomotive, while at the same time the wheels shall be so constructed that no difficulty whatever can be met with in turning the toy around in the arc of a circle; and with these ends in view my invention consists in the details of construction hereinafter fully described, and then specifically designated by the claims.

In order that those skilled in the art to which my invention appertains may more fully understand its construction and operation, I will proceed to describe the same in detail, referring by letter to the accompanying drawing, forming a part of this specification, which shows a side elevation of a toy locomotive constructed in accordance with my improvement.

I will not enter into any detailed description of the construction of the locomotive, as my improvement does not relate in any way to the same, but is only pertinent to the wheels.

A is the forward truck of the locomotive, having cast integral therewith or rigidly attached thereto the cow-catcher B. C is an axle supported within said truck, and having mounted thereon the wheels D. E is a flange, which projects at right angles to the rim of said wheels, for the purpose presently explained. F are small wheels mounted on the axle G, which is journaled within the truck H, rigidly secured to the frame or body of the device. I are driving-wheels having flange J, similar to those previously mentioned, and mounted on axles K, journaled within the body of the device, and L are also driving-wheels mounted on axles M. These driving-wheels have crank-pins N, which are connected

by lever O in the usual manner, so that motion will be imparted from one pair of wheels to the other.

From the foregoing it will be seen that the rear driving-wheels and the forward pair of small wheels are both constructed with raised rims or flanges, and accordingly it will be readily understood that when the locomotive is drawn along the floor the remaining or inside wheels, F L, will not touch. The advantage gained by this peculiar arrangement is that in turning the toy around in the arc of a circle there are only two points of contact with the floor—namely, at the front and rear—and this of course greatly facilitates the running of the toy. The pivoting of the front truck permits the movement of the locomotive to be readily controlled, and the rear driving-wheels act as a pivot on which the device is turned.

Prior to my invention toy locomotives have been constructed with one pair of drivers and small wheels, so that the toy may be readily turned around; but in order to preserve the resemblance to a locomotive full sets of wheels should be used, and this has hitherto been found to be inconvenient, owing to the excessive friction against the floor of so many wheels in alignment, and in turning the locomotive around suddenly it would invariably topple over. My improvement not only overcomes these disadvantages, but it preserves the general appearance of a locomotive in respect to the running-gear.

I am enabled to form the front and rear wheels of a diameter greater than that of the inside wheels, and thereby do away with the flange; but I prefer to construct them as shown, because they not only resemble more closely the ordinary flanged wheels of a locomotive, but are also cheaper in cost.

I do not wish to confine myself to the application of my improvement to a toy locomotive, as it is obvious that the wheels of toy vehicles generally may be constructed in the manner hereinbefore described with equal facility.

Having thus described my invention, what I claim as new, and desire to secure by Letters Patent, is—

1. A toy locomotive having two or more driving-wheels and two or more small wheels

on each side, the rear driving-wheels and the forward small wheels having flanged rims, and the intermediate wheels being free from contact with the floor or other surface, substantially as described.

5. 2. In combination with the wheels I, having flanges J, the pivoted truck A, cast integral with the cow-catcher B, and supporting the axle C, having mounted thereon the flanged wheels D, substantially as set forth.

3. The driving-wheels L, raised out of contact with the floor, and the flanged driving-wheel I, in combination with the lever O and crank-pins N, substantially as set forth.

In testimony whereof I affix my signature 15 in presence of two witnesses.

GEORGE S. CROSBY.
